UNITED STATES PATENT OFFICE.

EARL W. NEAL, OF NEW YORK, N. Y., ASSIGNOR TO WESTERN ELECTRIC COMPANY,
INCORPORATED, OF NEW YORK, N. Y., A CORPORATION OF NEW YORK.

HEATER.

1,405,064.

Specification of Letters Patent. Patented Jan. 31, 1922.

Application filed March 28, 1919. Serial No. 285,939.

To all whom it may concern:

Be it known that I, EARL W. NEAL, a citizen of the United States, residing at New York, in the county of Bronx, State of New York, have invented certain new and useful Improvements in Heaters, of which the following is a full, clear, concise, and exact description.

This invention relates to heaters and more particularly to a heater especially adapted for use in the manufacture of vacuum tubes. One type of vacuum tube has a base comprising a metal shell, which is attached to the neck of the tube by means of a cement comprising alcohol as a solvent. After the cement has been placed in position between the shell and the tube and has set, it is desirable that the alcohol solvent be thoroughly dried out.

It is the object of this invention to provide a heater for the above and similar purposes which is simple in construction and efficient in operation.

It is a further object of this invention to provide a heater in which the bases of a plurality of tubes may be dried simultaneously and inserted or removed individually without disturbing the condition of the other tubes in the oven.

With these objects in view, a plate-like electric heating element is employed, and the bases of vacuum tubes are held in position to receive the heat from the heating element by means of tubular sockets carried by a

plate of brass or other heat conducting material which lies adjacent the heating face of the heating element. The sockets are preferably of the same or similar material as the plate, and are provided with a latch or

equivalent means for holding the tubes in position. The oven, as a whole, is conveniently mounted for manipulation of the tubes with the heating element in horizontal position and the sockets depending downward therefrom.

The invention will be more fully understood from the following detailed description and claims taken in connection with the accompanying drawings, in which Fig. 1 shows in side elevation a heater embodying the invention, Fig. 2 is a bottom plan view of Fig. 1 with the supporting standards in section, and Fig. 3 is a detail sectional view on an enlarged scale on line 3—3 of Fig. 1.

Referring to the drawings by reference

numerals, standards 10, which may be of metal covered with asbestos, as at 11, support a horizontal plate 12 of brass or other suitable heat conducting material. Secured in circular openings 13 (Fig. 3) in plate 12 are tubular socket members 14. There is one row of sockets adjacent each longitudinal edge of the plate. Mounted above the plate 12 is an electric heating member 15, which may be, as shown, a standard heat unit, taking a current of about eleven amperes, at 110 volts. The body of heating member 15 is composed of insulating material 16 having embedded therein, near the lower surface, conductors 17 having a relatively high resistance to electric currents. Suitable connections therefrom to a source of heating current are provided, as indicated at 18.

A vacuum tube 19 is shown with its base inserted in one of the sockets 14. This tube 75 is one of the type above referred to, having a shell 20 attached to the neck 21 of the tube by means of cement 22. The pin 23 is one member of a bayonet joint (the other member of which is not shown), employed for 80 securing the tube in its position of use. Each socket 14 is provided with a slot 24 to receive the pin 23, and the pin 23 is engaged by a latch 25 for the purpose of holding the tube in position. These latches are mounted 85 for independent pivotal movement on a rod 26 adjacent each row of sockets. The latches 25 are each provided with a weighted operating lever 27, which normally acts to hold the latch in locking position. 90

While the preferred embodiment of the invention has been shown and described, it is to be understood that the invention is not limited to the exact structure and arrangement shown, but comprises the use of equivalents within the scope of the appended claims. 95

What is claimed is:

1. In a heater, heating means, heat conducting means connected to said heating means, a recess formed in said heat conducting means, and means for retaining in contact with conducting walls of said recess an article to be heated. 100

2. In a heater, a heating element, a socket 105 associated with said heating element, and means for retaining an article in contact with conducting walls of said socket.

3. In a heater, a heating element, a socket of heat conducting material associated with 110

said heating element, and means for retaining an article in contact with the walls of said socket.

4. In a heater, a plate-like heating element, a heat conducting plate adjacent to the heating face thereof, means for retaining an article in heat receptive relation to said conducting plate, and a support for said devices, said support comprising heat insulation.

5. In a heater, a plate-like heating element, a heat conducting plate adjacent to the heating face thereof, a socket of heat conducting material carried by said conducting plate, and means for retaining an article in said socket.

6. In a heater, a socket adapted to receive the base of a vacuum tube having a laterally projecting pin, a slot in said socket to receive said pin, and means adapted to engage said pin for retaining said base in said socket.

7. In a heater, a plate of insulating material, heating means embedded in said plate adjacent one face thereof, a socket of heat conducting material adjacent said face, said socket being adapted to receive the base of a vacuum tube.

8. In a heating apparatus, an electric heater, a plate of heat conducting material adjacent the heat emitting surface of said heater, and a socket in said plate adapted to receive the base of a vacuum tube.

9. In a heating apparatus, heating means, a socket adapted to hold an article in heat receptive relation to said heating means, and a latch for retaining said article in said socket.

10. In a heating apparatus, a heater, a metallic plate adjacent said heater, a series of article-holding sockets mounted on said plate, a rod mounted adjacent said sockets, and latches pivoted on said rod for holding articles in said sockets respectively.

11. In a heating apparatus, a heater, a socket connected thereto, and means for holding an article in said socket, said means comprising a pivoted latch having a weighted handle.

12. In a heating apparatus, a heater, a socket of heat conducting material connected thereto adapted to receive a vacuum tube, and yielding means for retaining said vacuum tube in said socket.

13. In combination, a base member having a socket member projecting therefrom, said socket being adapted to receive a vacuum tube having contact terminals, and means for yieldably holding said terminals against said base member.

14. In combination, a socket of heat conducting material adapted to receive the base of a vacuum tube and means for applying heat to said socket.

15. In combination, a socket adapted to receive the base of a vacuum tube, having a laterally projecting pin, and means for holding said vacuum tube in said socket, said means comprising a pivoted latch having a weighted handle, said latch being positioned to engage said pin.

In witness whereof, I hereunto subscribe my name this 26th day of March, A. D. 1919.

EARL W. NEAL.
